UNITED STATES PATENT OFFICE.

FRANK J. DIACONT, OF PROVIDENCE, RHODE ISLAND, ASSIGNOR TO THE WAITE, THRESHER COMPANY, OF SAME PLACE.

DESIGN FOR A HANDLE FOR BUTTON-HOOKS OR SIMILAR ARTICLES.

SPECIFICATION forming part of Design No. 31,734, dated October 31, 1899.

Application filed October 9, 1899. Serial No. 733,101. Term of patent 3½ years.

To all whom it may concern:

Be it known that I, FRANK J. DIACONT, a citizen of the United States, residing at Providence, in the State of Rhode Island, have invented a new and original Design for the Handle of a Button-Hook or Similar Article, of which the following is a specification, reference being had to the accompanying drawing, forming a part thereof.

- 10 In the accompanying drawing the figure represents the face view of a button-hook handle embodying my new design.

As shown in the drawing, the leading or material features of my design consist in the 15 transverse circular bead *a*, the scrolls *b b*, the branching ornament *c*, the longitudinally-curved hollow fluting *d*, which joins the longitudinally-curved hollow fluting *e* at the transverse line *f*, the flower ornament *g*, the 20 foliated scrolls *h h*, the foliated scrolls *i i*, the

scrolls *j j*, the foliated scrolls *k k*, with the central ornament *l*, the scrolls *m m*, the reverse scrolls *n n*, the panel *o*, the rows of beads *p p*, the foliated scrolls *q q*, the opposite shell ornaments *r r*, the beads *s s*, the knob *t*, with the club-formed branches *u u*, and the terminal foliated scroll *v*.

It is apparent that this design is also applicable to the handles of various similar articles.

Having thus described my invention, what I claim as new, and desire to secure by Letters Patent, is—

The design for the handle of a button-hook or similar article, as herein shown and described.

FRANK J. DIACONT.
